UNITED STATES PATENT OFFICE

2,435,138

COMPOUND INTERNAL-COMBUSTION
TURBINE PLANT

Fritz Albert Max Heppner, Leamington Spa, England, assignor to Armstrong Siddeley Motors Limited, Coventry, England

Application January 6, 1944, Serial No. 517,272
In Great Britain January 15, 1943

3 Claims. (CL 230—122)

1

This invention relates to a compound, internal-combustion, turbine plant having a contra-rotating shell from which useful work is taken, and particularly to such a plant for jet-propulsion purposes, the contra-rotating shell carrying externally jet-augmenter blades.

The specification of my co-pending patent application Serial No. 500,694, filed August 31, 1943, now matured into Patent No. 2,426,098, of August 19, 1947, discloses such a compound plant in which useful work is taken out between adjacent turbine sections, so that the pressure at the end of a compressor section is substantially equal to that at the beginning of the associated turbine section, whereby I avoid sealing problems, particularly at large diameters.

In the specification of my co-pending patent application Serial No. 500,695, filed August 31, 1943, now abandoned, the contra-rotating turbine shell coacts with independent turbine sections respectively coupled to compressor sections, and useful work is taken out of the gases and transmitted to the shell between most or all of the turbine sections, the shell being driven relatively slowly.

For perfect pressure balance between the turbine and compressor sections the speed should be uniform, i. e., all the sections should rotate at the same rotatable speed if the blade efficiency is constant throughout, but this raises difficulties in the design of the compressor, and regulation is entirely unsatisfactory.

It is my main object to avoid these disadvantages.

A further object is to design the shell to run more slowly than it would on the reaction of the compressor only, as in my applications above mentioned.

For an understanding of these and other objects and advantages of the invention attention should be directed to the following description in which reference is made to the accompanying diagrammatic drawings in which—

Figure 1 is a graph of the operation of a compound turbine according to the specification first aforesaid and Figure 1a of a turbine according to the invention;

Figure 2 is a part-sectional elevation of a turbine according to the invention;

Figures 3 to 5 are views mainly of one of the independent turbine and compressor stages, Figure 3 being a perspective view of the shell with the augmenter blades omitted and with one independent turbine and compressor stage shown withdrawn, whilst Figure 4 is an axial view there-

2

of and Figure 5 a fragmentary developed plan of the independent stage;

Figure 6 shows a temperature-entropy diagram of the turbine in design conditions, and Figure 6a in regulation conditions;

Figures 7 and 7a show corresponding pressure-volume diagrams; and

Fig. 8 is a diagrammatic illustration of the structure and arrangement of the turbine blading of Fig. 2.

According to one feature of my invention, a compound internal-combustion turbine plant comprises a number of independent compound rotors each carrying compressor and turbine blades, the latter coacting with blades on a contra-rotating shell, the compressor blades coacting with stationary compressor blades, and useful work is taken out of the contra-rotating shell between the various rotors, and additional useful work is taken out at the high-pressure end by reaction on stationary blades, the various rotors having higher rotational speeds as the volume decreases to achieve practically constant incidence of the whole blading under regulation and starting conditions.

It may here be stated that if the shell were not driven against the said other stationary blades the speed with which the shell would rotate would be determined by the compressor torque and the total amount of available useful work, because, if a certain compressor torque a is available and a certain amount b of useful work is available, the useful work can only be extracted if $a \times n \times K$ equals b , where n is the speed and K is a constant. Therefore,

$$n = \frac{b}{aK}$$

If the shell is to be driven more slowly (i. e., according to the invention) additional torque must be provided, whence

$$n = \frac{b}{(a + a^1)K}$$

where a^1 is the additional turbine torque.

Thus, the additional torque necessary to drive the shell may be provided by arranging for the gases from the combustion chamber to pass at high speed through stationary nozzles to the first row or rows (which is or are on the shell) of turbine blades, these blades being partly or wholly of the impulse type, whilst the next two rows of turbine blades (at least) are of the reaction type, the final rows (which are not on the shell) being independently rotatable with their associated

compressor rows and being aerofoil blades—i. e., well-spaced blades.

The result is that the turbine operates with optimum efficiency, inasmuch as losses at the high-pressure end are to a great extent regained in the low-pressure end of the turbine, which latter end is very efficient.

Referring now to the drawings, the graph of Figure 1 is of a turbine plant according to the specification first aforesaid, and that of Figure 1a of the plant shown in Figure 2. The vertical lines A represent independent turbine and compressor sections, the ordinates P representing pressure. The areas enclosed by the lines B, C represent unavoidable pressure-difference, the line B being for the compressor and the line C for the turbine in both graphs. With the arrangement of the invention the resultant area enclosed between the lines C and B is very much reduced, it will be observed.

Referring now to Figures 2 to 5, the plant illustrated is one in which the turbine 11 is disposed radially outwardly of the compressor 12, the flow through the latter being from the top to the bottom. The compressor comprises stationary blade rows 13, 13 and rotary rows 14, 14, the latter rows being fast with independent turbine rows 15, 15. The first independent turbine row 15a is mounted to revolve with a sleeve 16 carrying a plurality of compressor rows 14a co-acting with stationary compressor rows 13a.

The burning gases are led from the tubular members 18 to a stationary row of blades 19 forming nozzles through which the gases pass at high speed to the first row 20 of turbine blades mounted on the shell 21, these blades being partly or wholly of the impulse type. (The shell carries external augmenter blades 22 coacting with stationary augmenter blades 23.) The row of turbine blades 15a fast on the sleeve 16 rotates at high speed to drive the final highest pressure portion of the compressor, this row and the next row 24 (on the shell) being of the reaction type. The final independent rows 15 and coacting rows 25 on the shell are all of the aerofoil type. The arrangement and characteristics of the blades 19, 20, 15a, 24 and 15 are indicated diagrammatically in Fig. 8.

As will be seen from Figures 3, 4 and 5, the blades 15 are spaced from one another sufficiently to allow of assembly into the shell through the larger (upper) end thereof, the blades passing between the blades 25 fast with the shell. Figure 5 shows at 14b some of the compressor blades strengthened to carry the centrifugal forces.

Conveniently the shell 21 is mainly of aluminium, the blades 25 being riveted to sheet-metal, arcuate portions 27 having end clearance from one another when cold, as indicated at 28 (Figure 4), the portions 27 being riveted at 29 to aluminium ribs 30 with heat insulating material 31 interposed. Alternatively, the shell can be made from steel in one piece with the turbine blades 25 permanently fixed in it, this being possible by the new way of assembly as a consequence of the wide spacing of the turbine blades. This feature also allows of assembling and dismantling the shell without interfering with the balance, which is a very important point because of the relatively-great weight of the shell.

At 33 I show a drive shaft, for auxiliaries, passing through the hollow feed nozzle 34, the drive shaft carrying a gear 35 which is driven from the compressor sleeve 16 through a compound pinion 36 and gear 37.

As previously stated, perfect pressure balance asks for equal revolutionary speeds of all the compound members, but this interferes with regulation, i. e., operation at a reduced fuel supply, and it also interferes with constant Mach number on the compressor, because the rotational speed remains constant but the Mach number goes up with temperature. Furthermore, as the volume decreases higher revolutionary speeds and smaller dimensions are required to keep the wheels at their optimum proportions. The optimum compressor shows constant Mach number to reduce the number of stages. The replacement of a great number of counter-rotating discs by one shell gives the mechanical mechanism an aerodynamic rigidity, which must be made flexible to make the incidence constant on the blades in regulation conditions. This is done, according to the invention, by thermodynamic means, taking out a certain amount of useful work at the high pressure end of the counter-rotating shell against stationary turbine blades so that the high pressure compressor part is driven at a turbine pressure which is a certain amount lower than the corresponding compressor pressure. Then, in regulation conditions, the available work for driving the high pressure compressor becomes smaller because the diagram (see Figures 6a and 7a) must read as though the lines of constant pressure become more closely spaced towards the low pressure region. Therefore overspeeding of the high pressure part at partial loads is avoided, and the incidence on all the blades (turbine as well as compressor) can be kept practically constant throughout the whole range of regulation.

Additional practical advantages are—

- (1) Constant Mach number in compressor.
- (2) High temperature of turbine on slowly-running small-diameter shell part running under low stresses.

Referring to Figure 6, or Figure 6a, AB represents the rise in temperature in the compressor, assuming adiabatic compression, and CD the temperature drop in the turbine on the assumption of adiabatic expansion, whilst BC is a constant pressure line representing the heat taken in during combustion. ΔT_1 and ΔT_6 , on the line AB, represent equal temperature rises (i. e., equal increments of heat) in the first six compressor sections, and ΔT_7 the temperature rise in the last (highest-pressure) section—assuming seven sections altogether, while ΔT_1 to ΔT_7 on the line CD are the corresponding temperature drops for the turbine. The “useful work removed” at X represents the energy bleed against the stationary blades 19, i. e., the work done on the first shell blades 20. The dotted lines are constant pressure lines which are, however, given a “droop” adjacent the line CD pictorially to represent the modification introduced by the invention. In a similar way the dotted lines in Figures 7 and 7a are intended pictorially to indicate the alteration, due to the invention, in the P/V diagrams.

With regard to Figures 6 and 6a, consider the line B6—C6. The corresponding line B4—C4 in Figure 2 of my application aforesaid No. 500,694 is purely a constant-pressure line. In the present instance, however, the shell speed is lower. Therefore the amount of useful energy actually taken out between the first two compound discs 14x and 14y (see Figure 2) is less than that corresponding to the thermodynamic efficiency of that section of the engine. This accounts for the “droop” in the line B6—C6. For the same reason there is a “droop” in the line B5—C5.

which is greater than that in B6—C6, the corresponding compound discs being those marked 14y and 14z. And so on. In other words, the turbine portion of a compound section works at a lower pressure than the corresponding compressor portion. In consequence, in regulating down, i. e., at reduced fuel, the available work of the turbine portion decreases more quickly than would be the case if these "droops" did not exist, thus avoiding over-speeding of the highest-pressure portion of the compressor. I further effect a transfer of energy to turbine portions connected to low-pressure parts of the compressor which otherwise would be driven too slowly and would have negative incidence, giving low efficiency. When regulating down the speed fall in the lowest-pressure sections is greater than in the highest-pressure sections, as appears from a comparison of Figures 6 and 6a. The loss of work represented by these "droops" is made up for by the energy bleed X.

It will be understood that if one took the extra work X (Figures 6 and 6a) out at the low-pressure end instead of at the high-pressure end, instead of "droops" one would have "rises," and regulation effects would be opposite to those described, i. e., would be impossible.

Incidentally, the combined "droop" and "rise" shown in the line A—D is accounted for by the exhaust of the engine reacting against the diffuser blades.

Finally, it may be added that the term "Mach number" is here used in its ordinary significance, to denote, at a given temperature, the ratio of the speed of air (relatively to a blade) to the speed of sound. There may, of course, be different Mach numbers, for a given temperature, for the leading and trailing edges of a blade.

What I claim as my invention and desire to secure by Letters Patent of the United States is:

1. A compound internal-combustion turbine plant including a plurality of independent compound rotors each rotating in the same direction and carrying compressor and turbine blades, a shell rotating in the opposite direction to said rotors and carrying turbine blades coacting with said first-named turbine blades, said shell taking out useful work between said rotors, stationary compressor blades coacting with said first-named compressor blades, and stationary blades at the high-pressure end of the turbine blades, the ad-

jacent turbine blades carried by the shell coacting with said stationary blades to take out additional useful work at the high pressure end of the turbine, said blades being so constructed and arranged that the rotors have higher rotational speeds as the volume of gases decreases.

2. A compound internal-combustion turbine plant according to claim 1 wherein the stationary blades are stationary nozzles cooperating with the first row of turbine blades on the shell at the high-pressure end of the turbine and through which the combustion gases pass at high speed to said blades to provide additional torque for driving the shell, said blades being at least in part of the impulse type, at least two of the next succeeding rows of turbine blades being of the reaction type, and the remaining rows of turbine blades on the rotors being aerofoil blades.

3. A compound internal-combustion turbine plant including a plurality of independent compound rotors rotating in the same direction and carrying compressor and turbine blades, stationary compressor blades coacting with said first-named compressor blades, an output member in the form of a shell rotating in the opposite direction to said rotors and carrying rows of turbine blades coacting with said first-named turbine blades, the rotors having higher rotational speeds as the volume of gases decreases, at least part of the highest pressure turbine blades on the shell being of the impulse type, and stationary nozzles coacting with said highest pressure turbine blades and directing the hot gases to said blades at high speed, the next succeeding row of turbine blades after said highest pressure blades being mounted on the highest pressure rotor and being of the reaction type, and the next succeeding row of turbine blades being also of the reaction type and being fast with said shell and with a row of compressor blades.

FRITZ ALBERT MAX HEPPNER.
